UNITED STATES PATENT OFFICE.

DAVID F. HAYNES, OF BALTIMORE, MARYLAND.

DESIGN FOR A BOWL OR BASIN.

SPECIFICATION forming part of Design No. 19,575, dated January 14, 1890.

Application filed November 2, 1889. Serial No. 329,091. Term of patent 3½ years.

To all whom it may concern:

Be it known that I, DAVID F. HAYNES, a citizen of the United States, residing at Baltimore, in the State of Maryland, have invented and produced a new and original Design for a Bowl or Basin, of which the following is a specification, reference being had to the accompanying drawings, forming a part hereof.

Figure 1 is an exterior side elevation of the bowl, and Fig. 2 a top view of the same.

I describe the bowl as follows: The base A of the bowl is circular, as seen from the bottom, and its edge curved outwardly to where it connects with the wall B of the bowl, which is also curved outwardly toward its upper edge. The general line of the upper edge of the bowl, as seen from the top, is an ellipse, as indicated by the dotted line *a* which surrounds it. In the direction of the shorter diameter the edge of the bowl is waved both on the inside and outside, so as to give a common thickness to the wall at that part thereof. In the direction of the longer diameter the

wall is smooth or regular on the inside and fluted on the outside. All the flutes diminish in width as they approach the circular base, which is shown in dotted lines in Fig. 2. On the flutes or waves first described, which are three in number, are circular panels with foliated bands in relief. 30

I claim—

The design for a bowl herein shown and described, the same comprising the circular bottom or base, the curved sides extending from the base to the upper edge of the bowl, 35 which has a general outline of an ellipse and waved at the sides which are on the shorter diameter and fluted at the other sides, the flutes diminishing as they approach the base, and the larger flutes provided with circular 40 panels with a foliated band or border in relief, substantially as described.

DAVID F. HAYNES.
